(57) **CLAIM**

I claim the ornamental design for a mini-refrigerator for sports fan, as shown and described.

DESCRIPTION

FIG. 1 is a perspective view of a mini-refrigerator for sports fan showing my new design;

FIG. 2 is a right side elevational view thereof;

FIG. 3 is a top plan view thereof;

FIG. 4 is a left side elevational view thereof;

FIG. 5 is a front elevational view thereof;

FIG. 6 is a bottom plan view thereof.

FIG. 7 is a rear elevational view thereof; and,

FIG. 8 is a perspective view showing the mini-refrigerator for sports fan in use with a door thereof partially opened; the broken lines depict environmental structure for illustrative purposes only and form no part of the claimed design.
